UNITED STATES PATENT OFFICE.

FRIDOLIN POLZER, OF NORWALK, CONNECTICUT, ASSIGNOR TO THE E. H. HOTCHKISS COMPANY, OF NORWALK, CONNECTICUT, A CORPORATION OF CONNECTICUT.

STAPLE-DRIVING MACHINE.

Application filed December 18, 1922. Serial No. 607,525.

To all whom it may concern:

Be it known that I, FRIDOLIN POLZER, a citizen of the United States, residing at Norwalk, county of Fairfield, State of Connecticut, ⁵ cut, have invented an Improvement in Staple-Driving Machines, of which the following is a specification.

This invention relates to stapling machines and more particularly to that type ¹⁰ known as strip staple machines wherein each staple at the time it is driven is severed from a strip of integrally connected staples which is fed forwardly at each operation of the machine to bring the staples successively into ¹⁵ a position to be severed and driven.

It is an object of the invention to provide a construction which will sever and drive the individual staples and which will prevent clogging of the machine during the severing ²⁰ and driving operation.

It is also an object of the invention to provide a construction which will free itself should a staple fail to be properly driven or should several staples become wedged in the ²⁵ raceway or throat, so that there will be no clogging of the machine.

With the foregoing and other objects in view, I have devised the construction illustrated in the accompanying drawing, in ³⁰ which—

Fig. 1 is a partial longitudinal section and partial side elevation of a stapling machine showing the elements in normal position ready for a staple driving operation.

Fig. 2 is a similar view showing the elements in the position they occupy just prior to the staple severing operation.

Fig. 3 is a similar view showing the position of the several elements at the completion ⁴⁰ of the staple driving operation.

Fig. 4 is a transverse section immediately to the rear of the staple holding device with the parts in the position shown in Fig. 1.

Fig. 5 is a similar view with the parts in ⁴⁵ the position shown in Fig. 2.

Fig. 6 is a similar view with the parts in the position shown in Fig. 3.

Fig. 7 is a detailed view substantially on line 7—7 of Fig. 3, but showing a plurality ⁵⁰ of staples clinched one over the other at the bottom of the raceway.

Fig. 8 is a similar view indicating how the mechanism clears itself of these staples.

Fig. 9 is a bottom plan view of the front

portion of the housing substantially on line ⁵⁵ 9—9 of Fig. 3.

Fig. 10 is a sectional view substantially on line 10—10 of Fig. 2.

Fig. 11 is an end view of the slide.

Fig. 12 is a top plan view of the forward ⁶⁰ end of the slide, and

Fig. 13 is a sectional view through the forward end of the housing showing the slide and plunger in elevation, but showing the effect secured without the use of the staple ⁶⁵ holding device.

The machine disclosed comprises the usual base 10 mounted on suitable rubber or fibre supports 11 and carrying the anvil 12 adapted to coact with the plunger for clinching the staples in the usual manner. The base is provided adjacent the other end thereof with upwardly extending spaced ears 13 between which is pivoted the slide 14 by any suitable means such as a pin 15, this slide ⁷⁵ providing a support and guide for the staple strip, as indicated at 16.

This slide is mounted in the lower part of the housing 17 and secured therein by suitable means such as transverse pins or rivets ⁸⁰ 18. At the forward end of the housing are vertical grooves 19 forming guides for the plunger 20, and also forming the raceway or throat at the forward end of the slide for guiding the individual staples to the anvil ⁸⁵ after they are severed from the strip, the plunger having longitudinal ribs 21 guided in these grooves and this plunger is so arranged that the lower end 22 thereof coacts with the forward upper edge 23 of the slide ⁹⁰ 14 to sever these individual staples from the strip as the plunger is forced downwardly.

Within the housing above the slide are mounted the usual staple strip feeding and holding mechanism. In the present instance ⁹⁵ 95 the feeding and holding mechanism comprises a cam plate 24 pivoted at 25 and having spaced lugs 26 and 27 adapted to be engaged by a lug 28 on the plunger as the plunger is reciprocated to rock the cam plate ¹⁰⁰ 100 on a pivot and move the feed pawl 29 back and forth. This feed pawl is pivoted to the cam plate, as shown at 30, and has fingers at its forward end to engage between the individual staples in the usual manner. Beneath this feed pawl and straddled thereby is a holdback 31 pivoted at 32 and also provided at its forward edge with fingers ¹⁰⁵

adapted to engage the rear side of the individual staples to prevent backward movement of the staple strip as the feed pawl is moved backwardly. The feed pawl and holdback are held in engagement with the staple strip by the free arms 33 and 34 of a wire spring mounted on a pin 35. The cam plate may be provided with a slot 36 through which may extend a pin 37 to act as a stop for the cam plate especially to assist in assembling.

Secured to the upper end of the plunger is the usual hand knob 38 by which the plunger is forced downwardly for the staple setting operation, and between this knob and the top of the housing is the usual coiled spring 39 tending to retain the plunger in its uppermost position, and to automatically return it to this position after the staple has been set.

Engaging the rear of the plunger and movable with the same throughout a certain portion of its travel is a staple holding and straightening device indicated as a whole at 40. This device has two L-shaped fingers 41 spaced so as to straddle the connection between two staples on the strip, and to extend down between the first and second staple when the first staple is in severing position, the transversely extending parts 42 of these fingers being positioned between the prongs of the first and second staples and the longitudinally extending portions 43 being positioned just outside these prongs so as to prevent the staple bending backwardly under the pressure of the plunger during the severing operation, and also to guide the staple after it is cut to prevent its wobbling or turning out of position in the raceway and insuring that it reaches the paper in the upright position, and thus will be properly driven. If the first staple happens to be bent rearwardly on the strip these fingers will engage the prongs thereof and straighten it prior to the severing operation.

This element is operated as follows:

The lateral ribs 21 on the plunger are recessed to provide shoulders 44 which, under certain conditions, are adapted to engage the upper ends of the spring fingers 45 at the upper end of the straightening element 40, the fingers 41 of this element being connected by the cross-bar 46. The angle shaped fingers 41 engage on the outside and rear of the ribs 21 and slide within the vertical grooves 19 with the plunger for a portion of its movement. On the top of the housing about the plunger is mounted a cam plate 47 having lugs 48 extending under the spring fingers 45. When the plunger is in its uppermost position, as shown in Fig. 4, the lower edge of the cross-bar 46 rests on the top of lug 28 carried by the plunger with the ends of the fin-

gers 45 beneath the shoulders 44 and the lower end of fingers 41 are spaced above the top of the staple strip. A blow on the knob 38 will depress the plunger and through the action on the shoulders 44 and spring fingers 45 will move the straightener element 40 down with the plunger. At the time the plunger and straightener reach the position shown in Figs. 2 and 5 the lower ends of the portions 42 of the fingers 41 are inserted back of the first staple, and as the plunger is now in position to begin the severing of the first staple this staple will be held against bending. After the staple is severed the plunger and straightener move together carrying the severed staple along with them, and the plunger will drive the prongs of this staple through the paper and in coaction with the anvil 12 will clinch the same. On the downward movement of these elements, however, soon after the staple is severed, the lugs 48 on the cam plate 47 will engage under the curved part of the fingers 45 and will move the upper ends thereof outwardly from engagement with the shoulders 44 at about the time or just before the lower end of the fingers 41 engage the top of the anvil, as shown in Fig. 6. At this time the plunger has not yet reached the top of the anvil and this action of the lugs 48 will thus disconnect the straightener from the plunger and allow the plunger to move through the rest of its travel to clinch the staple while the straightener remains stationary. After the staple has been set and pressure removed from the top of the plunger the spring 39 will raise the plunger to its uppermost position ready for the next operation. As the plunger moves upwardly from its lowermost position the straightener 40 will remain stationary until the lug 28 on the plunger engages the underside of the cross-bar 26 then the straightener will move upwardly with the plunger. On the latter part of the downward movement of the plunger the lug 28 engages the cam lug 27 on the cam plate 24 moving the feed pawl 29 rearwardly over the next staple. When the plunger returns to its uppermost position, the lug 28 engages the upper lug 26 on cam plate 24 moving the feed pawl forwardly a distance equal to that between two adjacent staples, and advances the staple strip on the slide 14 to bring the next staple to severing position under the plunger. During the backward movement of the feed pawl the hold back 31 prevents the staple strip moving backwardly with the feed pawl.

The slide 14 for supporting and guiding the staple strip is of a width on its upper portion slightly less than the distance between the downwardly extending prongs of the staples indicated at 49 but is shown as being wider beneath these prongs, as indi-

cated at 50 and is of a width somewhat greater than the outside width of the staple. It will thus be seen the staple strip is guided by and has free movement along the upper 5 part of the slide. In the drawing the outside portions of the lower part 50 of the slide are shown integral with the same and act as spacing elements to properly position the slide in the housing 17, but these side portions 10 may obviously be made of separate flat strips of suitable thickness if desired, or may be formed on the housing, their purpose being to provide clearance spaces between the sides of the slide 14 and the housing at 15 the upper part of the slide to allow passage of the prongs of the staples.

It has been found in practice that sometimes under careless operation, especially if the plunger is depressed more than once 20 with no work to be attached beneath the plunger or without moving this work, that one or more staples may be jammed in the lower part of the raceway. Also when the straightener and holder 40 is not employed, 25 after the cutting edges of the plunger and slide become somewhat dulled a staple may be bent backwardly, as indicated in Fig. 13, and if the plunger is depressed the single staple might become jammed in the race- 30 way and clog the machine. In order to facilitate freeing of the machine under these conditions I have terminated the spacing elements 51 at a distance from the forward end of the slide as shown at 52, or in the 35 form shown have cut away the forward portion of the same to provide a free space beneath the staples on the opposite sides of this slide for the entire height of this slide at the forward end thereof, as shown 40 at 52, and the thickness of this part of the slide is not greater than the distance between the prongs of the staples. In other words there is a clearance space provided on each side of the slide for the entire height 45 thereof at its forward end between this slide and the walls of the housing and at the rear of the staple straightener to provide clearance for the staple prongs and allow the staples to drop or be easily forced out the 50 lower end of the raceway should they become bent out of shape or wedged therein. This clearance space for the staple prongs should preferably extend rearwardly from the front edge of the slide for supporting 55 the staple strip a distance substantially equal to the length of the prongs for the very best results, because then no matter how much the staple is bent it will not clog. However, as in actual practice the staples are 60 very seldom bent backwardly to the extreme position but usually only a small amount, any clearance for these prongs back of the fingers 41 of the staple straightening and holding device greater than the thickness 65 or gauge of the metal forming the prongs

is a decided advantage in reducing the liability of the staples to bind in the raceway, because in jamming there is a tendency for the prongs to turn at right angles or transversely of the strip and these clearance 70 spaces prevent their wedging in the guideways. Therefore, the greater the distance these clearance spaces extend to the rear of the straightening and holding device, or to the rear of the front end of the staple slide, 75 up to a distance substantially equal to the length of the staple prongs, the smaller is the liability of the staples clogging the machine and the more nearly fool proof the machine becomes. I do not, however, wish 80 to be limited to this last distance because, as stated above, any clearance space greater than the thickness of the staple prongs back of or to the rear of the straightening and holding means is a decided advantage over 85 a machine not provided with such clearance spaces. The front end of the spacing elements should preferably be spaced from the end of the slide a distance about equal to the length of the prongs of the staples when 90 no straightener 40 is used although this distance is not fixed and may vary considerably and may be considerably less than this amount especially if it is used with the straightening element 40. I also, in addition, preferably bevel off somewhat the opposite vertical edges of the front end of 95 the slide as shown at 53.

Referring to Figs. 7 and 8 I have shown two staples clinched on each other in the raceway, by way of illustration, although the mechanism will operate in the same manner with more of these staples. If there is no work beneath the plunger, these staples will be jammed in the raceway, and especially 100 between the forward walls of the grooves 19 and lower portions of the fingers 41, as shown in Fig. 7. If now the plunger is moved upwardly to its uppermost position the fingers 41 will be withdrawn from the 105 jammed staples, as shown in Fig. 8, and because of the space at the rear of the same on the opposite sides of the forward end of the slide 14 between it and the inner walls 110 of the housing, these staples are loosened and in most instances will drop out as soon as the forward end of the housing is raised above the anvil. If, however, they do not drop out of their own accord they are sufficiently loosened that if the knob 38 is struck 115 a sharp blow with the anvil and housing separated the fingers 41 will push the jammed staples out of the raceway completely clearing the machine.

In Fig. 13 the slide 14 is the same as that used in the other combination with the forward ends of the spacing elements 51 spaced from the forward end of the slide to provide space at the opposite sides of the lower portion of the front end of the slide. With 120 125 130

this layout the straightening and holding mechanism 40 is not used, so that there is nothing to positively hold this staple in its vertical position during the severing operation. It it should be bent, however, as indicated in Fig. 13, the space at the forward end of the spacing elements 51 allows the prongs to swing backwardly and the staple will not become jammed in the raceway.

10. To assist in the clearing operation I also prefer to cut away slightly the forward side of the lower ends of the grooves 19, as shown at 54.

15. It has been found in operation that by spacing the ends of the spacing elements or sides 51 away from the fingers of the staple straightening and holding means in a manner disclosed above clogging of the machine is effectively prevented, as any staple which 20 is not properly driven will either drop out of the raceway of its own accord or will be so loose in the same that it may be easily removed to clear the machine even when a large number of these staples are driven one 25 after another and on to each other in the raceway.

The clearance spaces at the sides of the slide at the forward end thereof also prevents breakage of the staple straightening and holding device 40. For instance suppose the prongs of the forward or first staple should be bent backward, as shown in Fig. 13. In this position if the spacing elements 30 51 extended to the forward end of the slide the ends of the prongs would rest on the top surface of these spacing elements. Then if the plunger and member 40 are depressed the fingers 41 must either cut the prongs of 35 the staple or the straightening and holding device will be broken because the tops of the members 51 prevent the staple moving to the vertical position. With the clearance spaces, however, there is nothing to prevent the staple straightening, so that the staple 40 will be moved to the proper position by the fingers 41 and then severed from the strip and set the same as if it had not been bent. However, as stated above, any clearance 45 spaces greater than the thickness of the staple prongs for the staple prongs back of the straightening and holding device is a decided advantage over machines not having these clearance spaces.

50. Having thus set forth the nature of my invention, what I claim is:

1. In a strip staple machine, the combination with a slide for holding and guiding a staple strip, a plunger coacting with the forward end of the slide to sever the individual 55 staples, means for advancing the staple strip to bring the staples successively to severing position, and means adapted to enter between the prongs of the first and second staples during the severing and clinching operation to hold the same, the forward end of

the slide being so arranged and proportioned that there is a clearance space for the staple prongs on both sides of the slide extending throughout the height thereof, said clearance spaces being of a width greater than 70 the thickness of the staple prongs and located immediately to the rear of the staple holding means when it is in the holding position.

2. In a strip staple machine, the combination with a slide for holding and guiding a staple strip, a plunger coacting with the forward end of the slide to sever the individual staples, means for advancing the staple strip to bring the staples successively to severing 75 position, and fingers operated by the plunger adapted for insertion between the prongs of the first and second staples to hold the same during the severing and driving operation, the forward end of the slide being so 80 proportioned and arranged as to provide on each of the opposite sides thereof a clearance space for the staple prongs after the staple has left the severing position, said clearance spaces being of a greater width 85 than the thickness of the staple prongs and located immediately to the rear of said fingers when they are in the holding position.

3. In a stapling machine, in combination, a staple strip carrying bar, a staple strip feeding means, means adapted to be inserted from above the staple strip between the prongs of two adjacent staples to straighten the same on the strip, and spacing means at the sides of the bar at the lower portion 95 thereof to provide spaces for movement of the staple prongs at the upper part of the bar, said spacing means terminating a distance greater than the thickness of the staple prongs to the rear of the straightening device to provide clearance spaces for the staple prongs immediately to the rear of the straightening device when it is in its lowest position.

4. In a stapling machine, in combination, 100 a staple strip carrying bar, a staple strip feeding means, and staple straightening means comprising fingers mounted so as to be insertable between the prongs of two adjacent staples from above the strip to 105 straighten the staples on the strip, there being clearance spaces for the staple prongs on the sides of the bar at the forward end thereof extending throughout the height of the bar, said clearance spaces being of a greater width than the thickness of the staple prongs and located immediately to the rear of said fingers, when they are in their lowest position.

5. In a stapling machine, in combination, 110 a staple strip carrying bar, a staple strip feeding means, and staple straightening means comprising fingers adapted to be inserted between the prongs of two adjacent staples to straighten the same upon the 115

- strip, there being clearance spaces for the staple prongs on the sides of the bar at the forward end thereof located immediately throughout the height of the bar, said clearance spaces being of a width greater than the thickness of the staple prongs and extending to the rear of the said fingers when they are between the staples.
6. In a strip staple machine, a slide for supporting the staple strip, a plunger arranged to coact with the forward end of the slide to cut the individual staples from the strip and to set said staples, and staple straightening and holding means arranged to be inserted between the prongs of the first and second staples on the strip, there being clearance spaces for the staple prongs at the sides of said slide at the forward end thereof extending throughout the height of the slide and extending rearwardly from said straightening and holding means when said means is in the holding position a distance greater than the thickness of the staple prongs.
- 25 7. In a strip staple machine, a slide for supporting the staple strip, a plunger arranged to coact with the forward end of said slide to cut the individual staples from the strip, and staple straightening and holding means operated by said plunger comprising fingers adapted to be inserted between the prongs of the first and second staples on the strip and downwardly from above the strip, there being clearance spaces for the staple prongs on opposite sides of said slide at the forward end thereof extending throughout the height of the slide and extending rearwardly from said fingers
- when they are in the holding position a distance greater than the thickness of the staple prongs.
8. In a stapling machine, in combination, a staple strip carrying bar, a staple strip feeding means, and staple straightening means comprising fingers mounted so as to be insertable between the prongs of two adjacent staples from above the strip to straighten the staples on the strip, there being clearance spaces for the staple prongs on the sides of the bar at the forward end thereof extending throughout the height of the bar and extending rearwardly beyond said fingers when they are in their lowest position a distance not less than substantially the length of the staple prongs. 55
9. In a strip staple machine, a slide for supporting the staple strip, a plunger arranged to coact with the forward end of said slide to cut the individual staples from the strip, and staple straightening and holding means operated by said plunger comprising fingers adapted to be inserted between the prongs of the first and second staples on the strip and downwardly from above the strip, there being clearance spaces for the staple prongs on opposite sides of said slide at the forward end thereof extending throughout the height of the slide and extending rearwardly beyond said fingers when they are in the holding position 70 a distance not less than substantially the length of the staple prongs. 65

In testimony whereof I affix my signature.

FRIDOLIN POLZER.
